UNITED STATES PATENT OFFICE.

MYRON C. STERLING, OF MIFFLINBURG, AND WILLIAM E. SALLADE, OF TURBOTVILLE, PENNSYLVANIA.

THREAD-CLEANING ATTACHMENT FOR TEXTILE MACHINERY.

Application filed September 2, 1924, Serial No. 735,375.

To all whom it may concern:

Be it known that we, MYRON C. STERLING and WILLIAM E. SALLADE, residing, respectively, at Mifflinburg, in the county of 5 Union, and Turbotville, in the county of Northumberland, both in the State of Pennsylvania, have invented new and useful Improvements in Thread-Cleaning Attachments for Textile Machinery, of which the following is a specification.

Our invention has reference, in its broad aspect, to improvements in thread cleaning and guiding attachments for use in conjunction with textile machinery, and with 15 respect thereto attention is invited to our prior patent on a similar attachment granted November 20th, 1923, Number 1,475,036. More particularly our present invention is 20 designed to remove slubs, waste, and the like, from silk, cotton, fibre or other thread stock whether in the raw, spun or thrown state, and at any stage in the process of its manufacture into the finished product.

Our present invention not only differs in 25 form from our previous attachment as described in the above identified patent, and other prior patented guiding and cleaning devices, but it also has certain advantages which are peculiar to it and are evidently 30 unattainable by the structures of these prior devices. In the first place we have provided a guiding and cleaning attachment which may be adjustably mounted as an entirety upon any desired portion of a textile machine, and which when so mounted may be 35 quickly and readily detached therefrom without employing special tools. Furthermore we have not only conceived of a unique method of effecting relative adjustability 40 between the cleaning blades, but we have provided a novel spring clip for detachably and adjustably mounting the guiding element of the invention in proximity with the cleaning element so that our device is easily 45 threaded and the proper tension maintained upon the thread stock.

To these and other ends which will hereinafter appear, our invention consists in the construction, arrangement and combination 50 of parts described hereinafter and pointed out in the claims forming a part of this specification and to which reference should be made in determining the scope of the invention.

One embodiment of our invention is rep-

resented by way of example in the accompanying drawing wherein:

Figure 1 is a front elevation of our thread cleaning and guiding attachment,

Figure 2 is a rear elevation of our invention;

Figure 3, an end view showing the manner in which the thread is fed to the guide and cleaning elements,

Figure 4, a perspective view of the cleaning element per se, and

Figure 5, a detail view of the spring clip which is employed to detachably and adjustably hold the guide element in place.

Like characters of reference designate like or similar parts throughout the several views of the drawing, in which:

The numeral (1) designates a base which is formed with an angular top face (2) provided with a groove (3). Seated in the groove (3) with its tang (4) rigidly engaging in the material of the base, is a double elliptical, one piece spring member (5) having terminal fingers (6) which are directed from opposite ends of the spring and are designed to detachably and adjustably engage a porcelain or metallic guide block (7). The guide block (7) is formed with an angular recess in its base designed to fit over the angularly formed top face (2) of the base and obviously upon the exertion of pressure at its ends it may be slid along the base to an extent determined by the over all length of the spring. To detach the block (7) it is slid past one of the fingers (6) and then released by moving it in the opposite direction. The block (7) is provided with a slot (8) for receiving the thread stock designated X in Figure 3.

Our thread cleaning attachment per se 95 comprises an angularly formed plate (9) having elongated openings (10) in the base portion (11) thereof through which screws are engaged to mount the plate on the base (1). When so mounted on the base, the 100 remaining portion (12) of the plate extends at an angle outwardly from the sides of the base, and integrally formed on the top edge of the portion (12) is a standard (13) which carries the fixed element (14) 105 of our thread cleaning attachment. An adjustable blade element (15) is formed with elongated openings (16) through which screws or the like engage to hold it in position upon the portion (12) of the plate 110

and beneath the element (14). The distance between elements (14) and (15) may thus, manifestly, be adjusted to accommodate different sizes and kinds of threads and the path of travel of the thread through such members may be regulated by adjusting the block (7).

While it is believed that the operation of our thread cleaning and guiding attachment is made clear in the foregoing, particular attention is invited to the fact that all parts are independently adjustable thereby facilitating and greatly increasing the sphere of usefulness of our device. The base member (1) may be either a permanent portion of a textile machine, or it may be detachable and adapted to be clamped or otherwise secured to a machine.

While we have in the foregoing elected to describe and illustrate only one form of our thread cleaning and guiding attachment it will be understood that we do not desire thereby to limit ourselves or confine our invention to the specific details of such form, except as may be defined by the scope of the claims subjoined hereto.

Having described our invention with such attention to detail as will enable one skilled in the art to understand its construction and advantages, we claim:—

1. An attachment for textile machinery comprising a base, a thread guide carried by the base, a thread cleaning element carried by the base, said thread guide and said thread cleaning element both being inclined

with respect to the base and extending therefrom on the same side thereof at relatively different angles.

2. An attachment for textile machinery comprising a base, a guiding element for thread carried by the base and inclined away from the vertical axis of the base, a cleaning element for thread carried by the base and arranged at a greater inclination from the vertical axis of the base than the guiding element and in the same direction, a spring member carried by the base for adjustably and detachably retaining the guiding element in place, said cleaning element being adjustably mounted on the base and means for adjusting the guiding element to compensate for different gauges of thread.

3. An attachment for textile machinery comprising a thread cleaning element formed with thread engaging members, means for adjusting one of said members with respect to the other, said cleaning element having an angularly formed body adapted to be adjustably attached to a base, and means for adjusting the path of travel of the thread through the cleaning members, said means including a spring pressed detachable and adjustable guiding block disposed in proximity with the thread cleaning element.

In testimony whereof we affix our signatures hereunto.

MYRON C. STERLING.
WILLIAM E. SALLADE,
